United States Patent

Des. 235,175
Patented May 27, 1975

235,175

GLOVE

Leonard Berger, Ridgewood, and Thomas H. P. Jaggers,
Jr., Ringwood, N.J., assignors to Rapid-American Cor-
poration, New York, N.Y.

Filed Apr. 29, 1974, Ser. No. 465,379

Term of patent 14 years

Int. Cl. D2—06

U.S. Cl. D2—373

FIG.3

FIG.4

FIG.5

FIG. 1 is a front elevational view of a glove embodying our new design;

FIG. 2 is a side elevational view of the glove shown in FIG. 1;

FIG. 3 is a rear view thereof;

FIG. 4 is a fragmentary enlarged view showing the detail of the design of the palm portion of the glove of FIGS. 1-3; and

FIG. 5 is a cross-sectional view taken along line 5-5 of FIG. 4.

We claim:

The ornamental design for a glove, substantially as shown.
